ATTORNEY

UNITED STATES PATENT OFFICE

CLAUD A. BOYD, OF FRISCO, TEXAS

ROD JOINT

Application filed May 9, 1932. Serial No. 610,174.

This invention relates to rod joints and its general object is to provide a joint primarily designed for rods used in wells and the like, that is capable of a swivel action which will prevent the rod from bending and twisting, therefore damage and breakage thereof will be reduced to a minimum.

A further object of the invention is to provide a swivel rod joint that includes latching means for detachably securing the rod sections together and the latching means is protected from obstructions and the like, therefore casual unlatching thereof is prevented.

Another object of the invention is to provide a latch actuated swivel rod joint that is relatively small so as to fit in well casings of all sizes now employed.

Another object of the invention is to provide a rod joint of the character set forth, that is simple in construction, inexpensive to manufacture and extremely efficient in operation and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views and in which:

Figure 1 is a perspective view of the rod joint which forms the subject matter of the present invention.

Figure 2 is a view partly in section with the parts of the joint associated.

Figure 3 is a longitudinal sectional view taken through the joint with parts in elevation.

Figure 4 is a perspective view illustrating a part of my rod joint.

Figure 5 is a sectional view taken approximately on line 5—5 of Figure 3.

Figure 6 is a sectional view taken approximately on line 6—6 of Figure 3.

Referring to the drawing in detail, it will be noted that I have illustrated my rod joint as including elements formed directly with

the ends of the rod sections A and B, but I want it understood that these elements may be secured to the rod sections in any manner without departing from the spirit of the invention.

The rod sections have formed with their upper ends the enlarged body portion of my joint and it will be noted that the body portion is tapered slightly and provided with a flat top while its base 2 merges into the rod B as best shown in Figure 4. Arranged between the base 2 and the body portion is a shoulder 3 for the purpose of receiving the lower edge of the cover 4 which is in the form of a sleeve.

The body portion has arranged therein a recess 5 which extends transversely from its outer wall, and disposed in communication with the recess 5 is a relatively small recess 6 that not only extends transversely from the outer side of the body portion but also extends through the top.

The recesses provide a chamber for the purpose of receiving the lower end portion of the section A, and this lower end has formed therewith a head 7 that is of a size to fit within the recess 5 and is engageable with the shoulders 8 disposed at the juncture of the recess 5 with the recess 6, so as to prevent longitudinal movement of the head within the chamber as will be apparent.

A portion of the lower end of the rod A above the head 7 is arranged in the recess 6, and by this construction, it will be apparent that the head and the adjacent end portion of the rod A is mounted for rotary movement within the chamber and is held therein accordingly through the instrumentality of the cover 4 which is provided with a lug 9 extending inwardly from the interior surface thereof for the purpose of being received within the recess 6. The inner face of the lug 9 is rounded to follow the curvature of the lower end of the rod A, and by providing the lug, it will be obvious that foreign matter cannot pass into the chamber which is formed by the recesses 5 and 6, therefore the head will be free to rotate as will be apparent.

Disposed laterally within the body 1 be-

low the recess 5 is a bore which communicates with the chamber 10 and mounted for movement in the bore is a pin 11 that is provided with a head 12 disposed within the chamber 10 that has also arranged therein a coil spring 13, the latter having its end convolutions engaging with the rear wall of the bore and the head 12 for the purpose of normally retaining the pin in its outermost position for disposal within an aperture 14 arranged in the cover 4 so as to retain the cover about the tapered portion of the body as clearly shown in Figure 3.

The spring pressed pin 11 and the aperture 14 constitutes the latching means for my joint and by the arrangement set forth, it will be noted that the latching means is protected from obstructions and the like so as to prevent casual unlatching movement thereof, with the result the cover cannot become casually removed, therefore it is practically impossible for the joint elements to become separated while the rod is in a well or the like, yet at the same time the joint 25 provides for a swivel action between the sections and such action prevents the rod from twisting which is the cause of most trouble in pump rods and the like. In pump rods now employed, the ends thereof are 30 threadedly secured together which results in the rod twisting and crystallizing the metal. When the metal becomes crystallized, it will be apparent that slight pressure will break the same, but such a casualty could 35 not happen to my device in view of the swivel joint.

It is thought from the foregoing description that the advantages and novel features of my invention will be readily apparent.

40 I desire it to be understood that I may make changes in the construction and in the combination and arrangement of the several parts, provided that such changes fall within the scope of the appended claims.

45 What I claim is:

1. A rod joint of the character described comprising a body portion having recesses formed therein to provide a chamber, headed means detachably and swivelly mounted 50 within said chamber, a cover surrounding the body portion, a lug formed with said cover and arranged in said chamber, said lug cooperating with the cover for securing the headed means within the chamber, and 55 a latching means for said cover.

2. A rod joint comprising a body portion provided with a chamber therein extending through the side and top thereof, a shoulder arranged in said chamber, a headed means 60 detachably and swivelly mounted within said chamber and having its head engageable with the shoulder, a cover surrounding the body portion and being provided with an aperture, a lug formed with the cover and 65 disposed within said chamber for engage-

ment with the head, said lug cooperating with the cover to retain the headed portion within the chamber, and a spring pressed pin mounted for movement in the body portion and received in the aperture to retain the 70 cover in operative position.

In testimony whereof I affix my signature.

CLAUD A. BOYD.
